(57) **CLAIM**

The ornamental design for a radar apparatus, as shown and described.

DESCRIPTION

FIG. 1 is a top, front, right side perspective view of a radar apparatus showing the new design;

FIG. 2 is a front view thereof;

FIG. 3 is a rear view thereof;

FIG. 4 is a left side view thereof; the right side view being a mirror image of the left side view;

FIG. 5 is a top view thereof;

FIG. 6 is a top, rear, left side perspective view thereof;

FIG. 7 is a perspective view showing the radar apparatus in an alternative configuration; and,

FIG. 8 is a perspective view showing the radar apparatus in an alternative configuration thereof.

The dash-dash broken lines represent portions of the article that form no part of the claimed design.

1 Claim, 8 Drawing Sheets
